UNITED STATES PATENT OFFICE.

LARS H. BERGMAN, OF CHICAGO, ILLINOIS, ASSIGNOR TO RAYMOND BROS. ENGINEERING CO., OF CHICAGO, ILLINOIS, A CORPORATION OF ILLINOIS.

BLOWING TANK FOR PNEUMATIC TRANSPORT SYSTEMS.

Application filed May 5, 1923. Serial No. 636,919.

To all whom it may concern:

Be it known that I, LARS H. BERGMAN, a citizen of the United States, residing at Chicago, in the county of Cook and State of Illinois, have invented certain new and useful Improvements in Blowing Tanks for Pneumatic Transport Systems, of which the following is a specification.

This invention relates to means for receiving, weighing and blowing into a transport line, a mixture of air and pulverized material, especially in such manner that the quantity of pulverized material so supplied to the transport line can be at all times definitely controlled and ascertained. More particularly, it relates to the connections and valves associated with a blowing tank for such a line.

It is an object of the present invention to provide more certain, simply constructed and easily operated means than have heretofore existed for providing an airtight closure at the point where the pulverized material is introduced into the tank.

It is a further object of this invention to more conveniently control the introduction of air into the tank, and particularly to effect a delivery of air in such a manner that the pulverized material is so aerated as to assume the characteristics of a freely movable fluid.

It is a further object of this invention to provide an outlet valve which shall deliver to the transport line either a mixture of coal dust and air or a stream of pure air.

It is a further object of this invention to provide for the control of the admission and mixture of air and powdered material, such as coal, and of the outlet or delivery valve from one convenient point.

It is a further object of this invention to provide means associated with the outlet valve for preventing settling of the coal dust at the bottom of the connection between the tank and the valve.

It is another object of this invention to provide an installation of the class described wherein the outlet from the blowing tank is controlled by a reciprocable plunger.

It is an important object of this invention to provide a blowing tank having such connections with the transport line that the

tank may be exhausted into the transport line after each introduction of powdered fuel into the tank, thus insuring definite control of the quantity of powdered material in each discharge. 55

Another object is to so construct the tank and its connections that they may be permanently installed in operative relations to 60 suitable scales for weighing the contents of the tank.

Other and further important objects of this invention will be apparent from the disclosures in the specification and the accompanying drawings. 65

The invention (in a preferred form) is illustrated on the drawings and hereinafter more fully described.

In the drawings

Fig. 1 is a side elevation partly in section of a tank embodying this invention. 70

Fig. 2^a is a vertical section through a four way valve employed in my invention.

Fig. 2 is an end elevation of the same. 75

Fig. 3 is a sectional view upon an enlarged scale of the slidable injector release valve shown in Fig. 1.

Fig. 4 is a detail showing the inner end of the slidable injector release. 80

Fig. 5 is an elevation showing a modification.

Fig. 6 is a vertical section through the injector release valve shown in Fig. 5.

Fig. 7 is a detail of the indicating dial. 85

As shown in the drawings the apparatus comprises a tank, adapted for mounting upon a scale, and arranged to receive powdered coal from a hopper. The coal admission valve is then closed air tight, air under pressure is admitted in such manner as to agitate and mingle with the powdered coal in the tank and until any desired pressure in the tank is attained. Then air and fuel are shot into the transport line under air pressure, and in any desired quantity. The air then scours out any deposited coal in the apparatus or transport line and the apparatus is ready to repeat the above operation. 100

The system includes a blowing tank 10, above which there is a hopper or storage tank 11 through which the pulverized material is introduced, preferably by gravity.

This hopper may be flexibly connected with the tank by a diaphragm 11^a constituting a flexible connection, permitting vertical movement of the tank, which is preferably supported upon weighing scales in any convenient manner. The hopper 11 discharges through a quick acting valve 12 operated by means of a cross-beam 13 and normally closed by a counter-weight 14. In order that the operation may be performed from a convenient point, chains 15 are connected to the two ends of the cross beam 13 and lead to a height above the floor which will bring them within easy reach.

15 The valve 12 opens into a hopper 10^a permanently mounted on the blowing tank 10.

Below the valve 12 is an air check gravity valve 16 which is operable by a rock-shaft 18 and lever 17. The outer end of the crank 20 lever 17 is provided with a link 19 having a hook 20 at its lower end, preferably at about the same height as the lower end of the chains 15. A handle ring 21 is also provided at the lower end of the link 19. 25 A ring 22 is provided for engaging the hook 20. This ring is swiveled upon the upper end of a screw 23, the lower end of which is provided with a handle wheel 24 for operating it. The screw is threaded 30 through a lug 25 secured to any convenient part of the frame of the apparatus. With the hook 20 engaging the ring 22, tightening the screw 23 will pull the hook 20 and the link 19 downwardly, causing the air 35 valve 16 to seat firmly against a gasket 26 provided at the bottom of a hopper 10^a which is between the valves 12 and 16.

By this arrangement of two valves, an air tight closure of the supply port is readily assumed, with no trouble from lodgment of fuel particles on the seat of the air check valve.

Air is supplied from any suitable source of compressed air through the pipe 30, having a flexible connection 30^a. 31 is a valve which, if desired, may be of any usual pressure reducing type. This pipe 30 leads to a four-way valve 32, which, as is shown in Figs. 2 and 2^a, controls communication with a pipe 33 leading into the top of the tank 10, a pipe 34 leading to the left to the transport line and a pipe 35 going downward. The valve 32 is of a well-known type, it may close the connection leading to ports 41 in the bottom of the tank or, in one position, it connects the pipes 33 and 34. In a second position it connects the pipes 30 and 33. In a third position it connects the pipe 30 and 35. A fourth position is possible in which the valve 32 connects the pipes 35 and 34, but it will be seen from the description given below that the mechanism for operating the valve 32 ordinarily does not bring it into this fourth

The pipe 33 connects through a horizontal pipe 33^a with the interior of the tank. Preferably the pipe 33 also extends to a safety valve 37. Preferably also the pipe 33 is connected to a pressure gauge 38.

70 The pipe 34, extends from the four-way valve 32, around the housing 39 to the fuel transport line 40, which has a flexible section 40^a. The junction preferably is by means of a welded joint.

75 The pipe 35 extends downwardly and, as shown at 35^a in Fig. 1, is connected with channel 42 in the casting at the bottom of the blow tank 10. This channel 42 (see Fig. 3) extends around this casting. Upwardly extending ducts 41 connect this channel with the interior of the casting so that the mouths of these ducts form a series of holes just below the upper mouth of the casting. As shown in Fig. 3, this casting provides at 43 a seat for gasket 45 of the coupling 44 by which the casting is united with the transport line 40.

80 Preferably the coupling 44 has a constricted passage to give greater effect to a stream of air when delivered through a nozzle 46 which receives air from a pipe 36 that joins the pipe 30 before the latter reaches the four-way valve 32. The pipe 36, throughout the greater portion of its length, is shown as parallel to the pipe 35. At its lower end the pipe 36 has a flexible section 47.

85 The pipes 35 and 36 are provided respectively with the hand valves 48 and 49 which may be set to control the rate of flow through said pipes. Ordinarily these valves will be set at a substantially permanent setting for any given installation.

90 The pipe 36 is supplied also with a valve 50 adjacent its junction with the pipe section 51, as shown in Figure 1. Pipe section 51 is rigidly connected with the sliding nozzle member 52, being screwed into a web 53 across said member. The sliding piece 52 reciprocates within a bearing 54 in this bottom casting and this bearing has the usual packing gland as illustrated. The sleeve 55 is slidably mounted upon the pipe 51, passes loosely through the right hand end of the sliding piece 52 and normally abuts the coupling 62, as shown in Fig. 3. A spring 56 surrounds the pipe 51, bears at one end against the web 53 and at the other end against the end of the sleeve 55, holding the sleeve against the end of the coupling 62.

95 The sleeve 55 is provided with oppositely arranged studs 57 for engaging the slotted ends 58 of a forked lever 59 by which the sleeve 55 and the nozzle member 52 are moved. The lever 59 rides over the quadrant 60 and is locked in its position by means of the usual arrangement 61. At the right of the sleeve 55, as shown in Fig. 3, a coupling 62 is provided which serves to couple pipe 100

51 with the flexible section 47 of the pipe 36.

The operating mechanism of the four-way valve 32 comprises a pulley wheel over which runs a chain 65. The lower end of this chain is led over a second pulley 66 upon a shaft 67 on the outer end of which there is a hand wheel 68 for the manipulation of the valve 32. A dial 69 is provided over which moves a pointer 70 integral with the handle 68. The dial 69 covers only a half of a circle because the valve 32 is ordinarily only operated through a half circle or less.

In the modification shown in Fig. 5, the tank 10 and hopper 11 are connected as already described. Air is supplied through a pipe 80 controlled by a valve 81. Pipe 80 has a flexible section 82. Pipe 80 is connected by a T with a pipe 84 which leads both to the top and the bottom of the tank 10. This pipe 84 is controlled above the T by a valve 85 and below the T by a valve 86. The valve 86 is separately hand operated. The valve 85 is connected with a lever 87 which simultaneously operates valve 86 and the moving parts of the blowing valve shown in Fig. 6.

The lower part of the pipe 84 is connected, by a horizontal pipe 88 to the housing of the blowing valve shown in Fig. 6.

The housing of the blowing valve encloses a channel or annular chamber 89 which has an upper set of ports 90 and a lower set of ports 91 opening into the interior bore or chamber. The sliding nozzle portion of the blowing valve has a relatively small cylindrical part 92 leading from its outer end 83 and extending through a stuffing box of the usual form at the lower end of the housing. Above this smaller part this sliding member is enlarged to a sliding fit with the annular web 89^a which forms the inner wall of chamber 89. This enlarged part 93 has an intermediate transverse web dividing the interior of the sliding member into chambers A and B. The wall of chamber B is provided with ports 95 adapted to cooperate with the ports 90. The wall of chamber A has ports 96 adapted to cooperate with the ports 91. Although but two ports 90 are shown and but two ports 91, there may be a circular series of each of these ports extending around the housing, in which event there would be a corresponding series of ports 95 and 96.

From the web 94 a nozzle 97 extends from chamber A through chamber B to the top of the sliding member and terminates in a nipple 98, extending into the lower end of the fuel transport line 40 which in this form extends through the interior of the tank 10 and emerges at the top thereof.

The lower end of the transport line 40 is provided with or secured to a casting providing a valve seat 99 supported by a spider 100 which is here shown as resting upon the housing or casting of the valve. This housing or casting may be secured, as shown in

Fig. 6, to the bottom of the tank 10 by any suitable form of bolts.

The enlarged part 93 of the sliding valve is provided with oblique ducts 101 above the ports 95 adapted to establish communication 70 between chamber B and the interior of tank 10. The enlarged part of the sliding member terminates in a conical end 102 which cooperates with the valve seat 99 to close the lower end of the transport line 40 when the valve is in its upper position. The link 102 on the end of the lever 87, through a collar 103 at the lower end of the valve, communicates motion from the lever to the sliding valve.

In the operation of the form shown in Fig. 1, pulverized material such as powdered coal is introduced into the hopper 11. The valve 32 is set to connect the pipes 33 and 34, which results in exhausting into the transport line any air pressure within the tank 10. The hand wheel 24 is then rotated to loosen the screw 23 so that the ring 22 is free of the hook 20. The link 19 is then manipulated by means of the handle ring 21 so as to open the valve 16 as valve 16 opens by gravity. The valve 12 is opened either before or after valve 16 by means of the chains 15 and coal from the hopper 11 descends to the tank 10. When the desired amount, as shown by the scales, has descended, the valve 12 is closed by means of the chains 15 and the valve 16 is closed by means of the link 19 and ring 21. Hook 20 is placed through the ring 22 and the hand wheel 24 is rotated to tighten the screw 23 until the valve 16 is seated firmly against the gasket 26. The valve 32 is then set to connect the pipe 30 with the pipe 33, and if the valve 31 is not already open, it is now opened. This causes air to pass from the supply line through the pipe 30, valve 31, the four way valve 32 into the pipe 33, from which it goes to actuate the gauge 38 and passes through the pipe 33^a into the tank 10.

In passing in it stirs the material within the tank and so mixes the air and the material effectually. The valves are left in this position until the gauge 38 indicates that the desired pressure has been reached. If through carelessness or ignorance the pressure is permitted to rise too high, the safety valve 37 will open and the tank will be protected. The valve 32 is now set so as to connect the pipe 30 with the pipe 35. The air which continues to enter the tank will now pass into the ducts 41 and so by entering the bottom part of the tank will still more effectually fill the same and tend to effect a thorough aeration of the material in the tank. This setting of the valve 32 is permitted to continue until the full pressure is developed in the tank 10. The valve 32 is then closed. The tank, however, continues to be protected against high pressure by

means of the safety valve 37 because the pipe 33^a is permanently connected with the pipe 33.

When it is desired to discharge from the tank into the transport line, the lever 59 is moved to the illustrated position. This brings the sliding part 52 of the valve shown in Fig. 3 into the illustrated position, opening port through 49 and air valve 50. Air and pulverized material, therefore, are blown through the opening 44 into the transport line.

The blowing of the material into the transport line 40 is assisted by air which passes through the pipe 30 down the pipe 36 and through the flexible connection 47 and valve 50 into the pipe 51, from which it passes through the nozzle 46 and creates a strong injecting blast through the constricted part 44. When sufficient material has been removed from the tank, as shown by the weighing scales, the lever 59 is operated, bringing the latch 61 into the upper of the two unoccupied notches shown in the quadrant 60 in Fig. 1. This moves the sliding member 52 shown in Fig. 3 sufficiently for its face 110 to contact with the gasket 45, thus closing part 44 and shutting off communication between the tank 10 and the transport line 40. During this motion of the part 52 by the lever, the sleeve 55 pressing against the spring 56 will cause the travel of the part 52. No compression of the spring 56 occurs until the shoulder 110 has seated against the gasket 45. Thus valve 50 remains open and air continues to blow into the transport line. The travel of the sleeve 55 corresponding to the described movement of the lever 59 goes beyond this point, this extra motion causing compression of the spring 56, thereby firmly holding shoulder 110 against gasket 43. As valve 50 and the flexible end 47 of the pipe 36 moves with sliding member 52, there is no relative motion between the valve 50 and the end 58 of the lever 59 until after the movement of the sliding member 52 is arrested. Consequently the valve 50 remains open. Air, therefore, continues to pass down the pipe 36 and through the nozzle 46, but pulverized material no longer enters the passage 44. This current of air to the transport line removes whatever material may be left in the line. When sufficient air has passed through the nozzle 46 for this purpose, the lever 59 is moved to the last notch in the quadrant 60. As forward movement of the nozzle member has been arrested the lever now moves the sleeve 55 along the pipe 51, thereby closing the valve 50. The yielding resistance of spring 56 permits this relative movement between lever 58 and pipe 51, which thus shuts off the flow of air through valve 50.

The valve 32 may then be returned to its "top" position so as to connect only pipes 33

and 34. Any remaining pressure in the tank 10 is thus relieved as air flows from the tank through the pipe 33^a, pipe 33, valve 32 and pipe 34 into the transport line 40. The tank is thus made ready to receive a further discharge of pulverized material, and the described operation repeated.

While the valve 50 is open as above described, the air which passes through the pipe 36 into the nozzle 46 sets up a current through ducts 111 which lead to the face 110. The currents from these ducts scour the bottom 113 of the casting free from any material which may have settled there.

In the operation of the form shown in Figs. 5 and 6, pulverized material is introduced in the same way as in the modification shown in Fig. 1. Air from pipe 80 passes through the T connection into the pipe 84. The position of the blow out valve 85 is then as illustrated in Fig. 6. Air passes down pipe 84 and through pipe 88 into chamber 89, through ports 90 and 95 and ducts 101 into the bottom of the tank, stirring up and aerating whatever material has tended to settle. If at the same time the valve 85 is open, air passes up the pipe 84 and enters the tank at the top. Pressure in the tank is thus built up by air delivered both at the top and the bottom of the tank. When the pressure has reached the required amount, the lever 87 is raised. This closes valve 85 and causes the main slide valve in Fig. 6 to descend. The descent of this valve closes the ports 95 and 101 and brings the ports 96 into register with the ports 91. Air now flows into chamber A, through nozzle 97 and emerges from the nipple 98 into the transport line 40. At the same time, valve 102 having been unseated from seat 99, mixed air and material pass from the tank 10 through the spider 100. The pressure in the tank is thus powerfully assisted by the injector action of air inflowing through the ports 96 and out through nozzle 97. Further assistance is given by air which flows from the pipe 80, past the open valve 81, through the flexible pipe 82 and enters at 83 into chamber A.

When a sufficient quantity of material has been delivered and by reversing the movement of the lever 87, the valve is returned to its illustrated position, the flow of air from the flexible pipe 82 continues until the transport line 40 has been cleared of material. If desired, this flow may continue at all times, or it may be stopped by closing the hand-operated valve 81.

The various flexible connections which are provided make possible the mounting of the tank on a weighing apparatus whereby the amount of material charged into and discharged from tank 10 may be determined by weight and controlled by manipulating the valves.

I am aware that numerous details of construction may be varied through a wide range without departing from the principles of this invention, and I therefore do not purpose limiting the patent granted otherwise than necessitated by the prior art.

I claim:

1. The combination with a blow tank for pneumatic conveying mechanism for powdered substances, of a transport line leading from said tank, an air supply conduit, other conduits leading respectively from said first named conduit to the top and bottom of said tank, a conduit leading to said transport line in advance of the entrance end thereof, a valve arranged to selectively connect two of said air conduits, whereby the valve in one position directs air from said supply conduit into the bottom of said tank and in another position directs air from the top of the tank to the said conduit leading to the transport line, and a separately controlled conduit leading from the air supply conduit to the entrance end of the transport line.
2. The combination with a blow tank, of means for admitting fuel thereto, air-tight means for closing the fuel admission passage to said tank, means for admitting air under pressure into said tank above the fuel contents therein, means for admitting air under pressure into said tank below the fuel contents therein, a transport line leading from the bottom of said tank, means for controlling the discharge of air and fuel from said tank to the transport line, independent means for exhausting air from said tank to the transport line independent of the fuel contents of said tank and means for independently discharging air under pressure into the transport line through said means for controlling the discharge of fuel.
3. The combination with a blow tank, of means for admitting fuel thereto, means for accumulating air pressure therein, a transport line, means for controlling the flow of fuel and air from said tank to the transport line, said means comprising a valve provided with a nozzle adapted to serve as a valve to control the discharge of fuel from the tank to the transport line, in combination with a second valve arranged to control the flow of air through said nozzle either simultaneously with the flow of fuel from said tank, whereby said nozzle serves as an air ejector to assist the fuel flow, or independently of the fuel flow, to scour the transport line.

4. In a device of the class described, the combination with a container for pulverized material and a conduit for conveying material from said container, of a valve adapted to close communication between said conduit and said container, said valve comprising a nozzle portion provided with an air ejector

nozzle, a body portion within which said nozzle portion is slidably mounted, a sleeve arranged to be reciprocated upon an extension of said nozzle portion, a spring interposed between said sleeve and said nozzle portion and means for reciprocating said sleeve.

5. In a device of the class described, the combination with a container for pulverized material and a conduit for conveying material from said container, of a valve adapted to close communication between said conduit and said container, said valve comprising a nozzle portion provided with an air ejector nozzle, a body portion within which said nozzle portion is slidably mounted, a sleeve arranged to be reciprocated upon an extension of said nozzle portion, a spring interposed between said sleeve and said nozzle portion, means for reciprocating said sleeve, an air conduit communicating with said nozzle portion, a valve controlling passage through said conduit and connections whereby said last named valve is only actuated when said sleeve is moved with relation to said nozzle portion.

6. The combination with a tank adapted to contain pulverized material, of a conduit arranged to receive and convey material from said tank, means for controlling the flow of material from the tank to said conduit and for accelerating said flow by an injector action, said means comprising a nozzle member adapted to be seated in said conduit to close communication between the tank and the conduit, said nozzle member being provided with a centrally arranged nozzle extending into said conduit, a body casting within which said nozzle member is slidably mounted, a compressed air conduit communicating with the interior of said nozzle member, a valve controlling the passage through said compressed air conduit, a sleeve slidably mounted with relation to said nozzle member, means for reciprocating said sleeve whereby said nozzle member is moved to and from its seat in the first named conduit and connections between said sleeve actuating means and said air conduit valve whereby said air conduit valve is only actuated during relative movement between said sleeve and said nozzle member.

7. In a device of the class described, the combination with a container for pulverized fuel, of means for discharging fuel from the container comprising a fuel discharge conduit communicating with said container, a nozzle movable to open and close said communication, an air conduit communicating with said nozzle, a valve controlling the passage of air through said nozzle, and operating means for said valve and nozzle having a lost motion connection with said nozzle.

zle, whereby the operations of the valve and nozzle are effected successively.

8. In a device of the class described, the combination with a container for pulverized fuel, of means for discharging the fuel from the container comprising a fuel discharge conduit communicating with said container, a nozzle movable to open and close said communication, an air conduit 10 communicating with said nozzle, a valve

controlling the passage of air through said nozzle, and means for operating said valve and for imparting movement to said nozzle comprising a lever connected to said valve and a resilient connection between said lever and said nozzle, whereby the operation of said valve and the movement of said nozzle may be effected independently of each other. 15

LARS H. BERGMAN.
